UNITED STATES PATENT OFFICE

136,747

DESIGN FOR A HANDBAG OR SIMILAR ARTICLE

Gerald Murphy, New York, N. Y., assignor to Mark Cross Company, New York, N. Y., a corporation of New York

Application May 20, 1943, Serial No. 110,241

Term of patent 14 years

To all whom it may concern:

Be it known that I, Gerald Murphy, a citizen of the United States, residing at New York, county and State of New York, have invented a new, original, and ornamental Design for a Handbag or similar article, of which the following is a specification, reference being had to the accompanying drawings, forming part thereof.

Fig. 1 is a face view of a handbag as it appears in open position, showing my new design.

Fig. 2 is a similar view in the closed position.

I claim:

The ornamental design for a handbag or similar article, substantially as shown.

GERALD MURPHY.
